William G. Johnston, Bridgetown N. S.

Letters Patent.

The schedule referred to in these Letters Patent, and making part of the same, containing a description in the words of the said William G. Johnston, himself of his improvement, being a machine for propelling machinery, called Johnston's inclined plane 'Barre' power.

Be it known that I, William G. Johnston of Bridgetown in the County of Lunenburg, and State of New-Bersey have invented a new and useful improvement in the useful arts; being a machine for propelling machinery, called Johnston's inclined plane 'Barre' power; which is as described as follows.

I make a frame, say nine feet long, two feet wide, (or of any convenient size) at each end and within this frame, are placed two heads or cylinders made in the following manner.— Take a piece of wood say twenty inches in diameter, two inches thick, with the periphery of the whole made therefrom planed down to a narrow neck in thickness, and hardened with iron. Two of these heads or cylinders are placed on a shaft so as to touch the outside edge of the receding floor hereafter described. At the other or lower end of the frame, I make two circular cylinders, but of ten inches diameter, of wood, iron or any suitable materials. They are placed at the end and within the frame before described, on a line so as to form on the periphery of the wheels or cylinders an inclined plane at an angle of about ten degrees, or as may be convenient, upon the inner side of the inclined plane, and at proper distances apart, friction

488.

friction wheels are placed off four inches diameter, or of any convenient size; these are placed one on each end of a shaft, secured by boxes to a plank forming the inclined plane, running on a line with the wheels or heads or cylinders at the ends of the frame first described. The parts forming the revolving platform, or stepping floor, I make as follows:— Two continuous round top chains are made from pieces of iron, or other material, with the straps joined together by iron links forming joints or hinges, four inches long each, or as may be convenient. Prepare plank, say four inches wide, fourteen inches long, and of proper thickness, and secure these to the round top chains by screws or rivets, parallel and close to each other. Set or nail the middle or middle, place one or more caps in each plank working in a middle head on the end of a horizontal shaft across the frame, and on the outer ends of each plank fit pieces of iron the width of the plank, bent at right angles to form a quarter circle. The revolving floor is placed within the frame, and over the cylinders and friction wheels.— The lead or nail passing over the friction wheels and cylinders. The caps in the plank forming the revolving floor, operate upon the middle head or wallow which is scorched immediately beneath the floor motion being given to the inclined revolving floor, by the power of the animal trampling thereon, in the manner of common inclined horse wheels. This communicates motion to the horizontal shaft in the center of the middle head; and this again conveys the motion to any machine required.

For a further illustration of my invention, refer to the model and drawing of the same.

same, deposited in the patent office.

What I claim as my invention and desire to secure by Letters Patent, is the combination and arrangement of the several parts of the machine, and the mode of applying the gearing by which the motion is obtained and communicated to all kinds of machinery in the manner hereinbefore specified and described.
